Primary Examiner—Celia Murphy

(57) **CLAIM**

We claim the ornamental design for a backpack with speakers, as shown and described.

DESCRIPTION

FIG. 1 is a front perspective view for a backpack with speakers showing our new design;
FIG. 2 is a top view of the backpack with speakers of FIG. 1;

FIG. 3 is a bottom view of the backpack with speakers of FIG. 1;

FIG. 4 is a front elevational view of the backpack with speakers of FIG. 1;

FIG. 5 is right side view of the backpack with speakers of FIG. 1;

FIG. 6 is a rear elevational view of the backpack with speakers of FIG. 1; and,

FIG. 7 is left side view of the backpack with speakers of FIG. 1.

The broken lines shown in FIGS. 1, 2, 5, 6 & 7, are understood to represent stitching.
